CONCRETE MIXER

Harold A. Wagner and Gustave H. Wagner,
Portland, Oreg.

Application August 8, 1942, Serial No. 454,106

7 Claims. (Cl. 259—166)

The present invention relates to concrete mixers, and more particularly to portable concrete mixing plants which are mounted upon an automotive vehicle chassis.

Large capacity concrete mixing plants are inherently relatively large, bulky pieces of machinery, and the mounting of such machines upon an automotive vehicle chassis inherently presents unusual problems of design. The arrangement of the drum, the concrete hoisting tower, the drum loading skip, together with the necessary driving and controlling means, as well as the various auxiliary apparatus, upon the vehicle in a compact, yet efficient, manner is essential in order that the weight and overall size of the machine may be maintained within reasonable limitations.

It is an object of the present invention to provide a new and improved structural arrangement in a vehicle mounted concrete mixing plant.

It is a further object of the present invention to provide in a vehicle mounted concrete mixing plant having a longitudinally mounted drum, a hoisting tower at the rear end thereof and a loading skip at the forward end thereof, a new and improved arrangement of a water accumulator tank in the forward end of the vehicle and which is compact in design and of sturdy construction.

It is a further object of the present invention to provide a new and improved chute arrangement for directing ingredients into the mixer drum from a loading skip pivotally mounted on the front end of the vehicle for hoisting ingredients from ground level to a dumping position above the forward end of the mixer drum.

It is another object of the invention to provide a new and improved structural arrangement in a vehicle mounted concrete mixing plant having a loading skip on the front end thereof and a hoisting tower on the rear end, the side frame structure being so designed as to guide upward pivotal movement of the skip, and to receive therebetween the tower unit when lowered to the inoperative position.

In accordance with the illustrated embodiment of the invention, a portable, vehicle mounted concrete mixer is provided having a frame with a mixer drum mounted longitudinally on the rear end portion thereof. A hoisting tower is pivotally mounted on the upper rear end of the frame behind the mixer drum, and a loading skip is pivotally mounted upon the forward end portion of the vehicle frame for hoisting dry ingredients from substantially ground level to a dumping po-

sition above the forward end of the mixer drum. A cab is provided in the forward end of the mixer vehicle from which the machine is controlled, particularly as when traveling between construction sites. The forward end of the vehicle frame is defined by a pair of opposite side frame members which guide the movement of the loading skip arrangement between the lower and uppermost positions. A water tank is provided between the opposite side frame members firmly bracing them apart and also providing a roof over the vehicle cab. A rear wall portion of the tank defines in part a chute for directing ingredients from the loading skip into the mixer drum. The upper wall of the tank is spaced somewhat below the upper extremity of the opposite side frame members so that a space is provided therebetween for cooperatively receiving the tower in the lowered position thereof. A pair of hinged plates are provided between the side frame members which, when the tower is elevated, may be raised to upright positions between the upper ends of the side frame members forming extensions of the chute for facilitating the charging of the mixer drum.

For a consideration of what is believed novel and invention, attention is directed to the following description taken in connection with the accompanying drawings, while the features of novelty will be pointed out with greater particularity in the appended claims.

In the drawings, Figure 1 is a side elevation of a vehicle mounted portable concrete mixing plant constructed in accordance with one form of the present invention and illustrated in the set up or operative condition; Figure 2 is a view of the same plant illustrated in Figure 1 but shown in the inoperative position as for traveling; Figure 3 is an enlarged longitudinal sectional view of the forward end of the mixer plant illustrating more particularly the arrangement of the water tank and drum charging chute; Figure 4 is a front end view of the upper portion of the concrete mixer taken along the line 4—4 of Figure 2; Figure 5 is a plan view of a portion of the concrete mixer illustrating more particularly the arrangement of the drum charging chute; and Figure 6 is a detailed view taken along the line 6—6 of Figure 3.

Referring to the drawings, particularly to Figures 1 and 2, there is shown a concrete mixing plant comprising a vehicle chassis supported upon front wheels 10 and rear wheels 11. A concrete mixing drum 12 is mounted upon the rear end of the vehicle with its axis extending longitudinally

of the vehicle chassis. Pivotedly mounted at the rear end of the drum 12, as at 13, upon the member 14 of the vehicle framework is a tower, indicated generally at 15, having a bucket 16 arranged therein for receiving mixed concrete from the drum 12 and hoisting it to desired heights. In the upright position the tower is adapted to be braced by members 17 extending to frame members 18 hinged as at 19 to the upper portion of the fixed framework of the machine.

An operator's cab 20 is provided in the forward end of the vehicle from which it may be controlled as during transportation of the plant between construction sites. Between the cab 20 and the adjacent end of the drum 12 is provided a space 21 within which is arranged such apparatus as water pumps, winches and miscellaneous driving and control means. For hoisting dry ingredients from ground level to dumping position above the forward end of the mixer drum 12 there is provided a loading skip 22 of a width substantially equal to the width of the vehicle and which extends across the forward end thereof. The skip 22 is pivotally mounted as at 23 between the outer ends of a pair of arms 24 which are pivotally attached at their other ends to the opposite sides of the mixer framework adjacent the forward end as indicated at 25. Cables 26 connected to the skip and trained over pulleys 27 on the upper ends of the hinged frame members 18 extend to winch drums 28 for effecting upward pivotal movement of the skip 22 over the forward end of the vehicle to dumping position thereabove.

The particular arrangement of the tower structure shown is more specifically disclosed and claimed in our copending patent application, Serial No. 460,362, filed October 3, 1942, entitled Concrete mixer tower. The specific arrangement of the loading skip structure illustrated is particularly disclosed and claimed in our copending patent application, Serial No. 442,630, filed May 12, 1942, entitled Concrete mixers.

The present invention is concerned primarily with the frame structure of the forward end of the concrete mixer plant shown, including a water tank and charging chute for the drum. In the construction of large capacity portable concrete mixing plants of the type herein considered, it will be obvious that the arrangement of the various parts contributing to the successful operation of the plant entails complicated problems of design in order that a most economical utilization of the available space on the vehicle chassis may be made, and also that the total weight and overall dimensions of the plant may be kept at a minimum, particularly to satisfy highway limitations as to clearances, weight restrictions, and the like.

In mixing large batches of concrete, a considerable quantity of water is required for each batch and, in order to cut down the time required for the preparation of each batch to a minimum, the requisite quantity of water should be available for dumping into the mixer drum substantially simultaneously with the charging of the dry ingredients thereinto. In the average construction project water supply conduits are of relatively small size so that a considerable amount of time would ordinarily be required to run the necessary amount of water directly into the mixing drum from the supply lines. Accordingly, it is desirable to provide a water storage tank on the concrete mixer plant and in which water may be accumulated during the period of concrete

mixing and discharging operations and held in readiness for the next successive charging of the mixer drum. The capacity of such an accumulator tank should be at least as great as the maximum amount of water required for each charging operation. In a large capacity concrete mixing plant it will readily be understood that the size of such a tank will be quite large and, accordingly, the matter of arrangement of such a tank on the vehicle chassis presents a considerable problem.

In the machine of the present invention, the water tank is provided in the forward end of the vehicle above the cab and between the opposite side frame members. It will be observed that the forward end of the mixer frame is defined in part by a pair of arcuate shaped members 31 extending in parallel vertical planes and arranged about a center corresponding to the pivotal mounting 25 for the skip supporting arms 24. These opposite side frame members 31 act as guides for stabilizing movement of the skip between lower and upper positions. The guides 31 being arranged between the skip supporting arms 24 are adapted to be engaged by rollers 32 provided on the arms 24 a corresponding distance from the pivotal mounting 25.

Referring now more particularly to the cross sectional view of Figure 3, the water tank, indicated generally at 33, will be described in greater detail. The opposite sides of the tank are formed by a pair of opposite plates 34 which are secured along their arcuate upper edges as by welding to the inner sides of the arcuate frame members 31, as well as to frame members 14 and 35. The tank is also formed by curved upper and lower walls 37 and 38 which are welded together along their forward edges as indicated at 39 and along their opposite sides to the side wall plates 34. The upper and lower walls 37 and 38 are preferably curved substantially as indicated, so as to impart increased rigidity thereto. The walls 37 and 38, while joined together along their forward edges, diverge from each other in extending rearwardly so as to define a considerable space therebetween. The rear wall of the tank is defined by a sloping plate 41 which is welded to the rear edges of the upper and lower walls 37 and 38, and also to the opposite side wall plates 34 forming an enclosure of considerable capacity.

With the structure thus far described it will be observed that the water tank acts substantially in the manner of a brace between the opposite sides of the mixer frame structure including the arcuate guides 31 and the forward ends of the frame members 14. The water tank, extending substantially from the forwardmost end of the mixer plant to a point immediately adjacent the forward end of the mixer drum also forms a roof over the operator's compartment or cab 20, as well as a roof over the auxiliary apparatus compartment 21 provided between the cab 20 and the forward end of the mixer drum.

In order that overall height of the mixing plant with the tower in the lowered position may be reduced to a minimum, for facilitating travel along right-of-ways having restricted overhead clearances and for lowering the center of gravity as much as possible, the uppermost wall 37 of the tank extends generally horizontally substantially in the plane of the pivotal axis 13 of the tower. The wall 37 of the tank is thus spaced considerably below the upper extremities of the side frame members 31 so that a space longi-

tudinally of the vehicle is defined within the upper forward portion of the frame structure for cooperatively receiving the tower unit in the lowered position as indicated in Figure 2.

A chute, indicated generally at 40, for directing the ingredients through the charging port in the forward end of the mixer drum is formed in part by the sloping rear wall 41 of the water tank 33, the lower portion of which wall extends below the tank proper as indicated at 43, while the central extremity thereof is of a reduced width defining the bottom wall of a spout 44 which extends through the mixing drum charging port. Opposite the sloping wall 41 is a vertical wall 45 which extends between the opposite side frames of the vehicle and is secured thereto as by welding. Secured between the sloping wall 41 and the vertical wall 45 are the pair of downwardly converging opposite side walls 46 and 47, as shown more clearly in the view of Figure 5. The spout 44 for the chute is further formed by an upper wall portion 48 secured to the lower end of the vertical wall 45 and a pair of opposite side wall sections 49. Hingedly secured along the upper edge of the tank wall 41 is a plate 51, of substantially the same width as the spacing between the opposite side frame members 31, and which in the raised position rests against stops 52 and 53 secured to the opposite side frames and which support the plate 51 in substantially the same angular position as the sloping rear wall 41. Hinged as at 55 to the upper edge of the vertical chute wall 45 is another hinged plate 56 of substantially the same width as the spacing between the opposite side frames and which is adapted to be secured in vertical alignment with the wall 45 by catches 58. With the hinged plates 51 and 56 in the upright position as shown in full line in Figure 3, an enlarged extension or hopper is formed above the upper end of the chute 40 which is sufficiently large so as properly to receive the contents being dumped from the charging skip 22. The capacity of the chute thus formed is sufficient for holding in the manner of a hopper the contents of the skip in the event that the skip is dumped at a rate faster than the contents can flow through the spout 44 into the mixer drum.

The chute extension plates 51 and 56, being hinged along their lower edges, may be folded downwardly to the dotted line positions as shown when it is desired to pivot the tower unit 15 to the lowered position between the opposite side frames of the vehicle. In the lowered position, the hinged extension plates 51 and 56 close the upper end of the chute and also thereby clear the space between the upper ends of the opposite side frames for the tower unit.

Means are provided for emptying the water from the tank 33 either directly into the mixer drum 12, or, preferably, into the chute 40. As shown more clearly in Figure 3, a pipe 61 extending through the lower wall 38 of the tank is connected to a pump 62 which in turn discharges through the pipe 63 into a corner of the chute 40 and beneath the baffle plate 65. The baffle plate 65, as noted more clearly in the views of Figure 5 and Figure 6, is securely welded along its opposite side edges to the rear tank wall 41 and the chute side plate 47 defining a triangular space therebetween and which is open at the lower end. Water being discharged from pipe 63 through the opening 66 in the tank wall 41 is deflected downwardly by the baffle plate 65 and because of the force and quantity thereof it acts 75

in the manner of a jet to force the ingredients dumped into the chute downwardly through the spout 44 into the mixer drum. It will be obvious that with this arrangement the water is pre-mixed with the dry ingredients before they pass into the mixer drum.

The tank 53 may be filled with water through any suitable connection (not shown) with a source of water supply.

Having described the principles of the invention in what are considered to be preferred embodiments thereof, it is desired that it be understood that the various specific details shown are merely illustrative, and that the invention may be carried out by other means.

We claim:

1. In a vehicle mounted concrete mixing plant having a cab in the forward end thereof and a loading skip pivotally mounted on said plant for hoisting ingredients from ground level to dumping position above said cab, the combination comprising a pair of arcuate opposite side frame members arranged concentrically with the pivotal axis of said skip for guiding the upward pivotal movement of said loading skip, means including a water tank extending the width of said vehicle for bracing said side frame members apart, the bottom wall of said tank defining the roof of said cab.

2. In a vehicle mounted concrete mixer having an operator's cab in the forward end thereof and a loading skip pivotally mounted on the forward end of the vehicle for hoisting ingredients from ground level to a dumping position above said cab, the combination comprising a pair of arcuate opposite side frame members for guiding movement of said skip between lower and upper positions, a water tank extending the width of said vehicle for bracing said side frame members apart, the rear wall of said tank defining in part a chute for directing ingredients from said skip into the mixer drum.

3. In a concrete mixer, the combination comprising a vehicle frame, a mixer drum mounted on the rear end of said frame with its axis extending longitudinally with respect to said frame, said mixer drum having a charging port in the forward end thereof, an operator's space on the forward end of said frame, a loading skip pivotally attached to said frame and extending beyond the forward end thereof, said skip being movable upwardly over said operator's space, a pair of arcuate guides forming the forward end of said frame for guiding upward pivotal movement of said skip, a water tank mounted in said frame above said operator's space, said tank extending the width of said frame between said opposite arcuate guides, the rear wall of said tank defining in part a chute for directing ingredients from said skip through said mixer drum charging port.

4. In a concrete mixer the combination comprising a vehicle frame, a mixer drum mounted longitudinally upon the rear part of said frame, said mixer drum having a charging port in the forward end thereof, a cab in the forward end of said frame, a loading skip extending across the forward end of said frame, said skip being pivotally attached to the opposite sides of said frame and being pivotally movable from ground level upwardly over said cab to dumping position above said drum charging port, the forward end of said frame comprising a pair of vertically arranged parallel arcuate guides on the opposite sides thereof for guiding upward pivotal move-

ment of said skip, said arcuate guides being arranged concentrically with the pivotal axis of said skip, means including a water tank arranged over said cab and extending between the opposite sides of said vehicle frame for bracing said arcuate guides apart.

5. In a concrete mixer the combination comprising a vehicle frame, a mixer drum mounted longitudinally upon the rear end of said frame, said mixer drum having a charging port in the forward end thereof, a cab in the forward end of said frame, a loading skip extending across the forward end of said vehicle frame, means pivotally mounting said skip to the opposite sides of said frame, said skip being pivotally movable from ground level upwardly over said cab to dumping position above said drum charging port, a pair of opposite side frame members for guiding upward pivotal movement of said skip, means bracing said side frame members apart comprising a water storage tank extending therebetween and supporting thereby above said vehicle cab.

6. In a vehicle mounted concrete mixing plant having a cab in the forward end thereof and a loading skip pivotally mounted for hoisting ingredients from ground level to dumping position above said cab, the combination comprising a pair of arcuate opposite side frame members for guiding the upward pivotal movement of said

loading skip, a water tank extending the width of said vehicle, the opposite side walls of said tank being rigidly secured to said arcuate side frame members for supporting said tank therebetween and for bracing said side frame members apart, the rear wall of said tank defining in part a chute for directing ingredients from said skip into the mixer drum, a hinged extension on said rear tank wall forming an enlargement of said chute in the raised position thereof, said extension closing said chute in the lowered position thereof.

7. In a vehicle mounted concrete mixing plant having a cab in the forward end thereof and a loading skip pivotally mounted for hoisting ingredients from ground level to dumping position above said cab, the combination comprising a pair of opposite side frame members for guiding the upward pivotal movement of said loading skip, means including a water tank extending the width of said vehicle for bracing said side frame members apart, the rear wall of said tank defining in part a chute for directing ingredients from said skip into the mixer drum, a discharge outlet for said water tank in said chute for expediting flow of ingredients into said drum and for premixing water with said ingredients.
